FIG. 2 is a side perspective view thereof; and,

FIG. 3 is a side elevation view thereof in a flex

The dashed broken lines and stipple shading shown in the side elevation view in FIG. 3 illustrates a surface that forms no part of the claimed design. The dot-dash broken lines in the drawings define the boundaries of the claimed design and form no part thereof. The remaining dashed broken lines in the figures depict portions of the catheter tip that form no part of the claimed design.
